SAFE

Anton Hofer and Felix Danninger, Milwaukee,
Wis., assignors to Edward J. Kastenholz, Mil-
waukee, Wis.

Application December 16, 1932
Serial No. 647,524

2 Claims. (Cl. 109—3)

This invention pertains broadly to safes for altar tabernacles, and is an improvement on our pending application filed January 21, 1932, Serial No. 587,892.

5 One of the primary objects of our present invention is to provide a novel operating mechanism for the doors of the safe or tabernacle, whereby to insure the easy operation of said doors and the effective locking of said doors against opening 10 movement by an unauthorized person.

Another salient object of our invention is to provide an improved lock structure for use with the safe, which is so constructed that actuation thereof without the correct key is rendered prac- 15 tically impossible, and whereby the barrel of the lock can be effectively utilized for actuating the various operating parts of the safe door-opening mechanism.

A further object of our invention is the pro- 20 vision of a sliding operating shaft operatively connected to the barrel of the lock through the use of a spiral slot and pin mechanism, so that upon release of the barrel, and rotation thereof, longitudinal movement will be transmitted to the said 25 shaft for releasing the locking mechanism of the doors, a novel means being provided for preventing the rotation of the said shaft during its initial longitudinal movement.

A further important object of our invention is 30 the provision of means for releasing the holding means for the said shaft after the same has released the locking mechanism for the doors, so that upon continued rotation of the barrel of the lock, the shaft will be permitted to revolve for 35 bringing about the swinging of the doors to an open position.

A further important object of our invention is the provision of novel means for constructing the key-operated lock for the safe, whereby the 40 same will not only be difficult to pick, but whereby wear thereon will be reduced to a minimum so as to insure the proper operation of the lock after long continued use, the tumbler plates of the lock being provided with hard steel bearing pins 45 against which the bit of the key is adapted to ride.

With these and other objects in view, the invention consists in the novel construction, arrangement and formation of parts, as will be 50 hereinafter more specifically described, claimed, and illustrated in the accompanying drawing, in which drawing:—

Figure 1 is a fragmentary bottom plan view of the safe, the doors being shown removed from 55 the swinging leaves or supporting arms, the

leaves or arms being shown in their closed, locked position.

Figure 2 is a view similar to Figure 1, showing the leaves or arms in their unlocked position and partly opened.

Figure 3 is a detail longitudinal section through a part of the lock and operating mechanism, the view being taken substantially on the line 3—3 of Figure 1 looking in the direction of the arrows.

Figure 4 is an enlarged fragmentary top plan view of a part of the operating mechanism, illustrating in detail the means for holding the operating shaft against rotation during its initial sliding movement.

Figure 5 is an enlarged detail side elevation of the rotatable barrel of the lock, showing the novel spiral shaft carried thereby for bringing about the actuation of the operating shaft.

Figure 6 is a fragmentary side elevation of the shank of a key utilized for operating the lock.

Figure 7 is a front elevation of the barrel of the lock, the face plate for the barrel of the lock being shown removed, and one of the tumblers partly broken away and in section to illustrate the structure thereof.

Figure 8 is a front elevation of the key utilized for operating the lock.

Referring to the drawings in detail, wherein similar reference characters designate corresponding parts throughout the several views, the letter A generally indicates an altar safe which can be constructed in accordance with our pending application referred to above.

The safe A is provided with a novel operating and locking means B for the doors of the safe, as will be hereinafter more fully set forth.

The safe A may comprise an end wall 10 having secured thereto, or formed thereon, a stub shaft 11 on which is rotatably mounted facing beveled gears 12 and 13. Any desired type of anti-frictional bearings 14 can be utilized for rotatably supporting these beveled gears, and the same have attached thereto supporting arms or leaves 15 and 16, which carry the closure doors for the safe (not shown). The safe is preferably provided with pairs of inner and outer doors, as fully set forth in our mentioned pending application, and the construction of the safe and actuating means for the inner door will not be described in detail in the present application, as the invention resides more particularly in the novel operating and locking mechanism, as pointed out in the objects.

Our improved operating and locking mechanism B comprises a hollow shaft 20, which is

rotatably mounted in suitable bearings 21 and 22 carried by the plate 10. These bearings 21 and 22 can be provided with conventional removable bearing caps or straps 23. The inner end of the hollow shaft 20 has formed thereon, or secured thereto, a beveled pinion 24, which meshes with the facing beveled gears 12 and 13 to bring about the rotation thereof when said hollow shaft is turned. This shaft is provided intermediate its ends with longitudinal slots 25, for a purpose which will be more fully set forth, and this shaft slidably receives the forwardly extending operating shaft 26, which extends beyond the front bearing 22. The forward end of the hollow shaft 20 can have secured thereto in any desired way a collar or bearing ring 27, which bears against the front face of the bearing 21, and holds the said hollow shaft against initial movement. Rearward movement of the hollow shaft is prevented by suitable washers 28 placed between the rear bearing 21 and the beveled pinion 24.

Slidably mounted upon the hollow shaft 20 is a sleeve 29, and this sleeve 29 is provided with a cup-shaped annular lock head 30, which is adapted to engage the hooked ends 31 of the lock arms or latches 32, which are secured to the swinging arms or leaves 15 and 16 when the said lock head is in its rearmost position.

Secured on the rear end of the sleeve 29 is a collar 33, and this collar carries a pin 34 which extends through the slot 25 into the operating shaft 26. This provides means whereby the operating shaft 26 and the sleeve 29 will move together as a single unit.

Disposed on the sleeve 29, and confined between the collar 33 and the keeper lock head 30, is a ring 35. This ring 35 has secured thereto rearwardly extending operating rods 36, which lead to certain operating mechanism for the doors, which form no part of the present invention. It will be noted that the collar or ring 35 is rotatably supported on the sleeve, but confined against longitudinal movement.

Novel means is provided for holding the sleeve against accidental rotation when the same is in its locked engaged position with the latch arms 32, and this means embodies a lug 37 formed on the rear face of the front bearing 22, which lug is received within a slot 38 formed in the forward end of the sleeve. This construction is more clearly illustrated in Figure 4 of the drawings. Obviously, when the shaft 26 is moved rearwardly, the sleeve 29 will be carried therewith, which will move the walls of the notch 38 from out of engagement with the locking lug 37. In view of the fact that the sleeve 29 is coupled with the shaft 26, the shaft is held against rotation when the walls of the notch are in engagement with the lug.

Disposed at the front end of the safe is the key-lock 40, and this key-lock 40 embodies a locking housing or casing 41, which is rigidly connected to a supporting bracket 42 bolted or otherwise fastened to the plate 10. Rotatably mounted within the lock housing or casing 41 is a barrel 43, and this barrel has formed thereon the cylindrical stem or shaft 44, which protrudes through the rear end of the bracket 42. This stem or shaft 44 is provided with spiral guideways 45, as is clearly shown in Figure 5 of the drawings. A key-hole 46, shaped to correspond to the key utilized in operating the lock, is formed in front of the housing or casing 41, and ex-

tending axially into the key-hole is a rigid guide pin 47 carried by the barrel or the lock.

Slidably mounted within the barrel 43 of the lock are oppositely disposed flat tumbler plates 48, which are normally urged outwardly from opposite sides of the barrel by means of spring-pressed pins 49 carried directly by said tumbler plate. The outer ends of the tumbler plates carry locking tongues 50, which are adapted to project into slots 51 formed in the lock casing or housing 41 when said tumbler plates are in their projected position. These tumbler plates are provided with central openings 52 which permits the insertion of the key into the barrel, and, in accordance with our invention, each of the tumbler plates are provided with guide and wear pins 53, which lie at the ends of the openings 52 adjacent to the spring-pressed pins 49.

These guide and wear pins 53 are preferably formed from hardened steel and form the means by which the tumbler plates are actuated by the key bit. As shown in Figure 7, the tumbler plates are provided with transversely extending bores 54, by means of which the guide and wear pins 53 are placed in position, and these guide and wear pins are held against accidental displacement by the spring-pressed pins 49. A cover plate 55 closes the open end of the barrel 43 and serves as means for retaining the tumbler plates in position.

Rotatably mounted on the cylindrical stem or shaft 44 is an operating collar or nut 56, and this collar carries diametrically disposed pins 57 which are received within the spiral grooves 45 formed in the said stem or shaft. Rigidly connected with the collar or nut 56 is the forward end of the operating shaft 26, and, if desired, the forward end of the shaft 26 can be provided with a disc 58, which forms means for abutting against the rear end of the collar or nut 56.

In order to facilitate the coupling of the hollow shaft 20 with the operating shaft 26, and to facilitate the guiding of said shaft 26, the forward end of the hollow shaft carries oppositely disposed rigid guide pins 59, and these pins are slidably received within sockets 60 formed in the collar or nut 56.

In Figures 6 and 8 we have illustrated a preferred type of key to be utilized with the lock, and, as shown, this key 61 embodies a shank 62 having the bit 63 formed on the forward end thereof. This bit 63 is provided with the desired type of indentations for facilitating the accurate depression of the tumbler plates 48 so that the locking tongues thereof will be withdrawn from all engagement with the walls of the slots 51 formed in the lock housing or casing 41.

In use of the improved structure, the key is inserted within the lock housing, and the guide pin 47 will ride into axial opening 64 formed within the shank 62 of the key. The initial movement of the key will depress the tumbler plates 48, which will allow the turning of the barrel 43 under the influence of the key. Upon initial turning movement of the key, the stem or shaft 44 will be rotated, and as the collar or nut 56 is held against movement by the locking engagement of the lug 37 with the walls of the slot 38, the nut or collar 56 will be fed rearwardly through the medium of the spiral grooves 45 and pins 57. This rearward movement of the shaft 26 will carry the lock head 30 from out of engagement with the latch arms 32, and the walls of the slot 38 may be out of engagement with the lock. Continued rotation of the key will now permit the shaft 26

and the hollow shaft 20 to rotate as a unit, which will bring about the opposite rotation of the beveled gears 12 and 13, and the consequent opening of the doors.

5 Upon retrograde rotation of the key, the doors will be closed, and when the same reach their extreme closed position, the gears 12 and 13 will be held against further movement. Consequently, the shaft 26 will be held against rotation, and 10 the nut 56 will be drawn forwardly toward the lock housing, and the parts will then reassume their locked position. The key can then be withdrawn, at which time the tumber plates will be projected by their spring-pressed pins into locking engagement with the stationary casing or 15 housing of the lock.

Changes in detail may be made without departing from the spirit or scope of this invention, but what we claim as new is:—

20 1. In a safe structure, a pair of facing beveled gears, door-hinge leaves connecting said gears, a hollow rotatable shaft having a pinion meshing with said beveled gears, means for rotatably supporting the hollow shaft, an operating shaft slidably mounted in the rotatable shaft, a key-operated lock including a rotatable barrel, a spiral shaft secured to the barrel, a feed nut on said 25 spiral shaft, means operatively connecting the

operating shaft with the nut, a lock sleeve slidably mounted on the exterior of the hollow shaft, means rigidly connecting the sleeve with the operating shaft, and cooperating locking means on the sleeve and one of the bearings for normally holding the sleeve against initial rotation, whereby initial rotation of the barrel will cause rearward movement of the operating shaft under influence of the spiral shaft and nut. 80

2. In a safe structure, a hollow shaft, bearings rotatably supporting the shaft, said shaft having longitudinally extending slots, an operating shaft slidably mounted within the hollow shaft, a sleeve slidably mounted on the hollow shaft, pins connecting the sleeve and operating shaft together extending through said slots, one of the bearings and sleeve carrying a coacting locking lug and slot, whereby the sleeve and operating shaft are normally held against rotation, a key-operated lock embodying a rotatable barrel, a spiral shaft connected to the barrel, and a travelling nut on said spiral shaft, means rigidly connecting the operating shaft and nut together, and guide pins carried by the sleeve and received within openings formed in said nut. 85 90 95 100
